MULTI-BLADE PLANER

Francis R. Everds, Estherville, and John H. Hanselman, Algona, Iowa

Application August 14, 1953, Serial No. 374,338

3 Claims. (Cl. 37—154)

The present invention relates to grading equipment and is more particularly concerned with the provision of an improved planing structure.

The maintenance of secondary, or non-hard surfaced roads requires continuous resurfacing. Roads such as dirt roads and gravel roads acquire through normal use, as well as through varying weather conditions, washboard effects and other similar surface irregularities. These irregularities must be smoothed out and the road material redistributed continuously or the conditions become aggravated to an extent which impairs traffic.

The present invention contemplates the provision of a novel planing board capable of resurfacing such roads at a minimum of expense both as to time and cost of resurfacing materials. According to the present invention, a multi-blade planer is provided which will handle the surface material a plurality of times at each pass and which will substantially reduce windrow losses. A novel means is provided for placing a resilient load upon the planer board for maintaining it in substantially fixed position relative to the road surface and the blade structure itself is constructed to cause leveling of the road surface ahead of the front wheels of the grading vehicle thereby preventing uneven movements of the grader and hence uneven movements of the planer board. By the provision of these features, a planer constructed according to the present invention permits the substantial elimination of the presently existing road surface defects at a minimum of time and effort.

It is therefore an object of the present invention to provide a multi-blade planer capable of operation ahead of the front wheels of the grader with which it is used.

Another object of the present invention is to provide an improved planer which is resiliently maintained firmly against the road surface.

Another object of the present invention is to provide a planer which is provided with positive means for providing forward movement of the planer and resilient means for maintaining the planer in position against the surface being graded.

Still a further object of the present invention is to provide a planer which may be readily adapted to existing road grading equipment.

Yet a further object of the present invention is to provide a planer which is extremely durable and which at the same time is constructed to be lifted away from the road surface without interfering with the running gear of the grader to which it is attached.

A feature of the present invention is apparatus securing the planer to the grader for adjusting the level of the former relative to the latter and which causes the planer to be adjusted vertically at all points to a substantially identical degree.

Another feature of the present invention is the provision of a three-point loading system for the planer which permits positioning of the planer against the surface to be graded in an equalized manner.

Still another object of the present invention is to pro-

vide a multi-blade planer capable of attachment to the super-structure of road graders now in existence by means of the power operated snow plow attachments thereon.

Still other and further objects and features will become at once apparent to those skilled in the art from a consideration of the attached sheets of drawings in which a preferred embodiment of the present invention is shown by way of illustration only.

On the drawings:

10 Figure 1 is a side elevational view in partial cross section showing the planer of the present invention in assembled position on a road grading vehicle;

Figure 2 is a plan view of the planer of the present invention taken along the line II—II of Figure 1;

Figure 3 is a detailed view of the loading mechanism for the planer, and

Figure 4 is a detailed view of the rear linkage for controlling the planer.

As shown on the drawings:

20 As may be seen from the drawings, the planer of the present invention is for use with a grading vehicle 1 having conventional frame members 2, 3, 4, and 5 and wheels 25, 25a. The planer comprises a box frame having a cross bar 10 constructed from I-beam or similar rigid material; 25 and a second cross member 11, which cross members maintain the side rails generally indicated at 12 and 13 in fixed position relative to one another. As may be seen from Figure 1 the side rails 12 and 13 are constructed from several pieces. The portions 12a, 13a are welded to the cross bar 10 and securely welded at their rearward ends to the portion 12b, 13b. The portions 12b, 13b are in turn welded to the rearwardly extending portions 12c, 13c. This arrangement provides a recess 14 beneath the axle 15 of the road grading vehicle, which recess provides clearance for purposes described below.

30 Rigidly secured, preferably by welding to the box frame, are the planing cutter blade support members 16, 17 and 18. These members are, for simplicity, constructed from structural members having an L-shaped cross section and 40 are positioned with the leg of the L facing downwardly toward the road and positioned toward the front of the road grader 1. By rigidly securing the supports 16, 17 and 18 to the frame comprising the members 10, 11, 12 and 13, the frame is angularly rigidified thereby providing an overall planer structure which is substantially inflexible in all directions.

35 Specially hardened planer cutter blades 19, 20 and 21 are secured by means of bolts 22 to the supports 16, 17 and 18. These cutting blades directly contact the surface 50 of the road or other surface to be leveled and will, under heavy duty conditions, gradually become worn. Provision of the bolt type attachment means 22 permits the removal of the worn cutter blades for sharpening, or for replacement in case of extreme wear or other injury.

45 By providing the cutter blades 16 and 17 in an open V relationship to the side rails 12 and 13 and by likewise providing the splitter blade 21 at an angle behind the opening, the road surfacing material ahead of the grader is leveled by the cutting blades and the material is pushed backwardly along the cutter blades 16 and 17 filling in irregularities. Finally the excess passes through the opening 23 and against the splitter blade 21 from which the material passes to the manufacturer's mold board 24 which is standard equipment on substantially all road and surface graders in use today. While the blades 16 and 17 are shown at an angle relative to the side rails 12 and 13 of approximately 45°, it is to be understood that this angle may be varied if desired.

50 By utilizing this blading relationship the material is handled at least three times in its passage from the road surface immediately ahead of the blades 16 and 17 to the position immediately behind the manufacturer's mold

board 24. This continuous rehandling of the material permits the maximum in filling and leveling action and greatly reduces the number of passes required to completely level the road surface.

Placement of the cutting blades 16 and 17 ahead of the grade vehicle wheels 25 substantially improves the leveling action of the present equipment since the surface reaching the wheels 25 has become substantially leveled through the passage of the cutter plates 16 and 17 prior to the time the wheels contact the surface. Therefore, the frame of the grading vehicle tends to maintain itself in a substantially level condition throughout its travel along the uneven road surface. By utilizing this advantage in combination with the planer control structure described below, applicants have been able to provide far superior surfacing action to that known in the prior art.

One of the major difficulties found in prior art planer structures was the degree of bounce or jump found in the planer. This was caused by the fact that the planers used in the prior art were in most cases maintained against the road surface by their own weight, or were inadequately maintained in forced contact with the road surface. Thus, in situations of severe rutting or washboard effect, the planer blading would have a tendency to provide a chattering action rather than a smooth leveling. Further, the planer would, under such circumstances, vibrate to such a great extent that the grading vehicle would be required to proceed at a relatively slow pace. Often times under such circumstances the prior art planing equipment could not be used at all and it became necessary to first utilize deeply cutting blades to remove a major portion of the ridges before a planing board could be utilized. By providing a firm downwardly and forwardly acting force against the planer of the present invention, the planer has become useful in resurfacing all types of surfaces, whether only mildly irregular or deeply rutted.

The structure provided for controlling the planer consists of a parallelogram raising and lowering mechanism in combination with a pair of downwardly angling thrust arms. In grading vehicles adapted for use with snow plow attachments, the arms 26 are in most cases already provided for that use and the planer structure is constructed to utilize this portion of the standardized equipment.

Movement of the planer in the vertical direction is, of course, guided by the pivoting arms 26 but is primarily controlled by the spring loaded links 30. The links 30 are slidably mounted through the slide blocks 31 which are in turn pivotally mounted within the bearings 32 by means of the trunnions 33. The bearings 32 are fixedly secured to the box frame by means of the platforms 34 secured to the side rails 12 and 13 and supported by means of the cross straps 35 welded to the cutter blade supports 16 and 17 respectively.

As may be seen from a consideration of Figure 3, the link 30 has, threaded to its lower end, a nut 36 or other similar fastening means of sufficient diameter to prevent removal of the link 30 from the slide block 31. A spring 37 is positioned between the slide block 31 and an abutment washer 38 rigidly secured to the link 30, thereby urging the slide block 31 to a position abutting the nut 36. Movement of the link 30 in a vertical direction will thus lift the planer by means of the nut 36 acting upon the block 31 which is in turn pivotally secured to the planer super-structure. With the arm positioned as shown in Figure 1 however the planer is maintained firmly against the road by the spring 37 which is somewhat compressed under normal planing operations.

The link 30 is maintained in the position shown in Figure 1 by means of a crank arm 39 rigidly secured to a shaft 40. The shaft 40 is in turn actuated in a clockwise or counterclockwise direction by means of a transmission of conventional design enclosed within the housing 41 and under control of the operator of the grader vehicle from the driver's position. While the transmission may be of any conventional design it is preferred that it be ir-

reversible, such as for example of the worm gear type. Such a provision permits the ready adjustment of the position of the link 30 without permitting loads applied to the link 30 to react back through the transmission to cause a change in the adjusted position thereof.

In order to maintain the planer in a level condition at all times, the present invention provides means for lifting the rear of the planer simultaneously with the front and to substantially the same degree. This means comprises a parallelogram bell crank linkage having a bell crank arm 42 rigidly secured to the shaft 40 and the arm 39, a reciprocating connecting link 43, bell crank arm 44 and a transmitting bell crank arm 45 which is pivotally secured to the lifting link 46. The bell crank composed of the arms 44 and 45 is pivotally mounted about the point 47 and the lifting link 46 is pivotally secured at 48 to the bracket 49 secured to the cross member 11.

Thus, it will be seen that rotation of the bell crank comprising the arms 39 and 42 will simultaneously cause an equal movement of the bell crank 44, 45. Thus, when the link 30 is lifted in its upward direction by movement of the bell cranks 39, 42, the lifting link 46 will simultaneously be moved vertically upwardly. This results in the movement of both the front and the rear of the planer simultaneously along a path which is substantially vertical.

As may be seen from Figure 4, the lifting links 46 form a triangle with the pivot bar 47 of the bell crank 44, 45. This triangular construction provides a single point of contact at the central portion of the cross bar 11 and permits a universal joint action providing a relatively large amount of automatic angular adjustment of the planer relative to the frame of the grading vehicle. It has been found that this three point loading permits superior equalization of the load of the planer on the road surface and hence permits a more accurate surfacing action.

When the planer is vertically lifted by means of clockwise rotation of the shaft 40 and hence the bell crank 39, 42, the portions 13b of the side rails 12 and 13 respectively move upwardly toward the vehicle axle 15. By providing the cut out portion between the members 12a and 12c and 13a, 13c, the planer frame may move upwardly to surround the axle 15 and the conventional steering tie rod link 50. This permits movement of the planer a distance sufficient to clear the usual obstructions in the road and thereby permits the grading vehicle to move from place to place without causing any planing or other contact between the planer and the surface over which the grader is traveling.

While the planing structure and the apparatus for controlling it herein disclosed have been shown in connection with a road surface grading vehicle of the type in general use, it is to be understood that the planing board of the present invention is readily usable for other purposes than the surfacing of roads. For example it may be utilized in the initial grading of all types of earth surfaces, and is also useful in surfacing earth roads with gravel or other material which must be evenly laid. It is further to be understood that the planer attachments herein shown may be utilized with different types of grading vehicles, the only essential being the provision of means for rotating one or the other of the bell cranks 39, 42 or 44, 45, or in the alternative, of reciprocating one of the links 30, 43 or 46 to thereby permit control of the planer frame.

It is understood that variations and modifications may be made in accordance with the concepts disclosed in the present application without departing from the scope of the novel concepts of the present invention.

We claim as our invention:

1. A planing board for cooperation with a grading vehicle comprising a frame, first and second cutting blades rigidly secured to said frame for positioning at points

ahead of the vehicle front wheels for movement of surface material from the sides of said frame to the center thereof, a splitter blade secured crosswise in back of and in line with the opening between said cutting blades at a point behind the vehicle front wheels, and three point load applying and lifting means associated with said frame whereby said cutting blades are maintained in resilient contact with the graded surface by means of bars positioned at two spaced points at the front of said frame and single load applying means centrally secured at the rear of said planing board whereby said planing board may effectively adapt itself to the general contour of the surface being planed.

2. A planing board for cooperation with a grading vehicle comprising a frame, first and second cutting blades rigidly secured to said frame at points thereon ahead of the vehicle front wheels for movement of surface material from the sides of said frame to the center thereof, a splitter blade secured crosswise to said frame in back of said wheels and in line with the opening between said cutting blades, and three point load applying and lifting means associated with said frame whereby said cutting blades are maintained in contact with the graded surface by means of bars positioned at two spaced points at the front of said frame and a single load applying means at the rear of said planing board whereby said planing board may effectively adapt itself to the general contour of the surface being planed, said single load applying means comprising a substantially universal pivot connection.

3. In combination in apparatus for grading rough surfaces, a vehicle having front wheels and a planing board extending from a point in front of said wheels to a point behind said wheels, cutting blades positioned at the front of said frame at a point ahead of the wheels, a splitter blade secured to said frame crosswise thereof at a point behind said wheels, and means for maintaining said blades in equalized contact with said surface, said means comprising rigid thrust means urging the front 10 of said board forwardly and downwardly into contact with said surface, auxiliary resilient means for resiliently urging said board downwardly toward said surface at spaced points ahead of said wheels and a pivotally mounted link secured to said board behind said wheel for maintaining the rear of said board in contact with said surface.
